UNITED STATES PATENT OFFICE.

ALFRED F. CANNON, OF MEMPHIS, TENNESSEE.

IMPROVEMENT IN MEDICAL COMPOUNDS OR OINTMENTS.

Specification forming part of Letters Patent No. 147,898, dated February 24, 1874; application filed January 22, 1874.

To all whom it may concern:

Be it known that I, ALFRED F. CANNON, of Memphis, in the county of Shelby and State of Tennessee, have invented certain new and useful Improvements in Ointment for Piles; and do hereby declare the following to be a full, clear, and exact description of the invention, such as will enable others skilled in the art to which it pertains to make and use it.

Cannon's salve for piles is composed of hog's lard and hog's hair, flavored with the essence of cinnamon or other flavoring substance. The said ointment is made in the proportions of one pound of hog's lard and two ounces of hair, and made by rendering the lard, or by melting the same with the hair until the hair is

dissolved or melted in the lard by heat, after which the composition is flavored with the essence of cinnamon or other flavoring, and when cold to be applied externally to the piles or affected part, whether external or internal.

What I claim as my discovery or invention is—

The compound of hog's hair and hog's lard, substantially as herein set forth.

In testimony that I claim the foregoing I have hereunto set my hand this 16th day of January, 1874.

A. F. CANNON.

Witnesses:

M. D. WELSH,
J. J. HEINRICH.
